UNITED STATES PATENT OFFICE.

HARRY M. PFLAGER, OF ST. LOUIS, MISSOURI, ASSIGNOR TO TRANSOM DRAFT GEAR COMPANY, OF ST. LOUIS, MISSOURI, A CORPORATION OF DELAWARE.

CAR-UNDERFRAME.

1,021,375.

Specification of Letters Patent. Patented Mar. 26, 1912.

Application filed October 20, 1909. Serial No. 523,581.

To all whom it may concern:

Be it known that I, HARRY M. PFLAGER, a citizen of the United States, residing at St. Louis, in the State of Missouri, have 5 invented a new and useful Improvement in Car-Underframes, of which the following is a specification.

My invention relates particularly to means for reinforcing the body-bolsters and middle 10 longitudinal sills and subsills thereat, of a car underframe, and has for its object to relieve the bolts or fastenings of the body-bolsters to the middle longitudinal sills from sheer stress, and to increase the strength and 15 rigidity of the underframe thereat against the stress of the draft-gear.

It consists in features of novelty as hereinafter described and claimed, reference being had to the accompanying drawing forming 20 part of this specification, whereon,

Figure 1, is a top plan view of my improved brace or reinforcing member applied to a car body-bolster (broken away), and to the middle longitudinal sills and 25 subsills (indicated by dotted lines in Fig. 1, and by full lines in Figs. 2, 3, and 4,) thereat; Fig. 2, a vertical longitudinal section thereof on line 2, 2, in Fig. 1; Figs. 3, and 4, vertical transverse sections thereof to enlarged scale, on lines 3, 3, in Figs. 1 and 2 and 4, 4, in Fig. 2, respectively, omitting the body-bolster, and Fig. 5, a vertical longitudinal section to enlarged scale through the 30 brace on line 5, 5, in Fig. 1.

Like letters and numerals of reference denote like parts in all the figures.

a represents the two middle longitudinal sills of a car underframe having the body-bolster *b* attached thereto on their undersides in the ordinary manner, and *c* the subsills which extend longitudinally between the body-bolsters beneath the sills *a* as hereinafter more particularly referred to, all the said parts being shown broken away.

d is a reinforcing member or plate composed preferably of cast steel integral throughout and of any suitable configuration and cross section, preferably in the present case consisting of a middle portion 45 1 which extends across and is adapted to bear, preferably for the entire distance between the middle longitudinal sills *a*, flatwise against the top of the body-bolster *b*, to which it is secured by bolts 2 as shown, the middle portion 1 being perforated cen-

trally and registering thereat with the vertical opening 3 through the body-bolster *b* for the king-bolt (not shown), and the middle portion 1 being formed at its ends with depending flanges 4 which overlap and are 60 adapted to bear against the front and rear edges (or sides) 5 of the bolster *b* which is thereby interlocked with the member *d*.

From the bottom of each depending flange 4 extends horizontally for a suitable length 65 or distance therefrom, the corresponding end portion 1' of the member *d* having its width equal preferably, to the distance between the outside upright faces of the middle longitudinal sills *a* against the underside 70 of which it is adapted to bear, and to which it is firmly secured, preferably by bolts 6, the inner edge of each end portion 1' beneath each sill *a* having an upwardly projecting flange 4' which corresponds in alignment with the flange 4 and bears therewith against the edge 5 of the bolster *b* at the top. Along the top of the member *d*, preferably 75 in alignment with the inside face of each sill *a*, is formed a suitably shaped strengthening rib 7.

The end portion 1' of the member *d* rearward of the bolster *b* is formed at its outer end beneath each middle longitudinal sill *a*, with a vertical depending flange 8, which is united to the end portion 1' along the same, by a suitable strengthening rib 9, and is adapted at its outer face to bear against the adjacent end of the subsill *c* which extends beneath and against the sill *a* to the corresponding flange 8 of a similar member to *d* applied to the bolster (not shown) and sills *a* at the other end of the car underframe, while the end portion 1' forward of the bolster *b* is preferably plain as shown.

In the above construction, by adapting the middle portion 1 of the member *d* to straddle and, conjointly with the inner flanges 4' of the end portions 1' to interlock with the top portion of the body-bolster, combined with the connection of the middle longitudinal sills *a* together by the end portions 1', and the abutting of the subsills *c* against the rear end of the member *d*, the body-bolster is prevented from lateral play and the underframe thereat greatly strengthened against the stress of the draft-gear, whether applied thereto in the ordinary manner, or directly to the body-bolster, as indicated by dotted lines in Figs. 1 and 2. 110

What I claim as my invention and desire to secure by Letters Patent is:

In a car underframe, the combination with a body bolster and the center sills of the underframe, of a reinforcing member, which is readily detachable from the body bolster by vertical movement of said reinforcing member, or said bolster, which reinforcing member comprises a center plate overlying the center of the body bolster, longitudinally extending vertically disposed ribs integral with the sides of said center plate, the ends of which ribs project equal distances in front of and to the rear of the ends of the center plate, horizontally disposed plates integral with the projecting ends of the longitudinally extending ribs, which last mentioned plates occupy a plane below the plane occupied by the center plate, thereby forming transverse shoulders at the ends of the

center plate which bear against the front and rear edges of the body bolster, vertically disposed plates integral with the rear ends of the pair of rearwardly projecting plates, which vertically disposed plates bear directly against the ends of the subsills of the car underframe, vertically disposed reinforcing webs integral with the inner edges of the vertically disposed plates and the corresponding pair of horizontally disposed plates to the rear of the center plate, means for rigidly fixing the center plate to the top chord of the body bolster and means for fixing the pairs of ribs to the center sills of the car underframe.

HARRY M. PFLAGER.
